PRINTING TELEGRAPH SYSTEM

Clyde J. Fitch, Endwell, N. Y., assignor to International Business Machines Corporation, New York, N. Y., a corporation of New York

Application December 28, 1940, Serial No. 372,111

3 Claims. (Cl. 178—23)

The invention relates to a printing telegraph system of the start-stop type, and more particularly to such systems adapted for two-way communication.

The present application is based on the unidirectional system disclosed in the co-pending application Serial No. 370,675, filed Dec. 18, 1940.

In the said co-pending application, the code groups of impulses are generated electronically under control of an impulse distributing means, which is actuated, step-by-step, a predetermined number of times, during each signaling cycle. Oscillatory means are provided for effecting energization of the actuating means of the impulse distributing means, and for controlling the conductivity of the electronic discharge devices employed for generating the impulses. Each transmitting and receiving station is provided with the impulse generating and distributing means just mentioned. At the transmitting station, upon each operation of the control switches, the oscillatory means and impulse distributing means are set into operation, for the duration of a signaling cycle, to generate code groups of impulses, during the cycle, in accordance with the settings of the control switches. The generated impulses are effective to control suitable signal transmitting means, the initiated signals of which, in turn, are effective to set into operation, each signaling cycle, these oscillatory means and impulse distributing means at the receiving station for controlling the energization of the control magnets thereat in accordance with the character signals received.

In the present application, each station is provided with a single impulse distributing means, associated oscillatory control means and impulse generating means. A send-receive switch provided at each station conditions the various control circuits so that the system is capable of initiating and sending code groups of signals with the switch in one setting, and receive the signals and print the characters with the said switch in another setting. Provision is also made, whereby the frequency of the oscillations generated for transmitting purposes may be different from the frequency of the generated oscillations when the system is employed for receiving purposes. The adjustments for controlling the different frequency rates are undisturbed when switching from sending to receiving, and vice versa. With the provision of this feature, communication between different stations is simplified, particularly when the frequency rates for the different stations vary in each instance,

Therefore, an object of the present invention resides in the provision of a start-stop printing telegraph system employing oscillatory control means for controlling the actuation of the distributor means each signaling cycle, and wherein the signal initiating means can be conditioned to be effective to transmit code groups of signals under control of the distributor means with the oscillatory means set for operation at a certain frequency rate, and the signal receiving means can be conditioned to be effective to be responsive to code groups of signals under control of the said distributor means with the oscillatory means set for operation at a different frequency rate without affecting the said setting for obtaining the transmitting frequency rate.

Other objects of the invention will be pointed out in the following description and claims and illustrated in the accompanying drawings, which disclose, by way of example, the principle of the invention and the best mode, which has been contemplated, of applying that principle.

General description

The printing telegraph system to be described is of the start-stop type, wherein a continuous signal or current condition is impressed upon the transmission medium at the times character signals are not impressed thereupon.

Referring now to Fig. 1, at the transmitting

station, the control switches or contacts C1—C6 and CS are connected to stationary brushes of the impulse distributing means, indicated generally by the reference character D, which brushes B1—B6, BP, BS, and BC1—BC3 cooperate with a plurality of movable conducting rings 10—13 which are actuated, step by step, by the control magnets 25 and 26.

The said contacts C1—C6, and CS, which are controlled permutatively, in accordance with the character selection operations, may be positioned directly by the permutation bars of a suitable transmitting unit, generally designated 85, such as described in U. S. Patents Nos. 1,214,515 and 2,161,564, or as is well known, may be positioned under control of suitable storage relays controlled by the devices referred to, in said patents, as for example, the storage relays described in the latter patent.

An oscillatory means, in the form of an electronic oscillator T1, is provided for controlling the alternate energization of the impulse distributing means actuating magnets 25 and 26, a predetermined number of times, each signaling cycle. An impulse generating device T3 is also provided, and arranged so that the conductivity of the triode sections thereof are controlled by the oscillatory means, in synchronism with the alternate energization of the control magnets 25 and 26. Thus, during the signaling cycle, when the impulse distributing means are released and actuated, upon operation of the control contacts, timed impulses are generated by the device T3, in accordance with the contact settings to control the signal generator 67 accordingly.

At the receiving station, impulse distributing means, oscillatory control means, and impulse generating means similar to those of the transmitting station are provided. The control magnets M1—M6 of a suitable teleprinter means 86, such as described in U. S. Patents Nos. 1,128,422 and 2,165,247, are connected to the stationary brushes of the impulse distributing means, so that the said magnets are energized in different combinations corresponding to the character signals transmitted for effecting recording of the corresponding characters.

With reference to Fig. 10, a send-receive switch S is provided at each station to condition the associated control circuits so that upon setting the switch, in one status, the contacts C1—C6, and CS are effective to control the distributor means and oscillatory control means to initiate the code groups of signals, and, in another status, the magnets M1—M6, and MP are rendered effective to be responsive to the code groups of signals which are impressed thereupon under control of the said distributor and oscillatory means. A pair of variable capacitor means TVC and RVC are provided for controlling the frequency rates of the oscillations generated by the said oscillator for signal transmitting and receiving purposes, respectively. Upon altering the status of the switch S, it will be shown that the setting of each capacitor means remains undisturbed, thereby simplifying the transmitting and receiving operations at the different stations.

Before describing the specific operations of the system, the individual control units and the uni-directional signaling system will be described first. The impulse distributing means will now be explained in detail.

Impulse distributing means

Referring now to Figs. 2 to 4, the impulse dis-

tributing means is shown to comprise a plurality of conducting rings 10, 11, 12 and 13 which are fixedly mounted on a common shaft 9 suitably journaled in the supporting frame 21. Centrally located on said shaft, and secured thereto, is an insulating spacer sleeve 14 to which in turn is secured a driving ratchet 15. Two spring urged actuating pawls 16 and 17, which are adapted to cooperate with the teeth 18 of ratchet 15, are pivotally supported by the arms 19 and 20, respectively. The latter are rotatably mounted in the supporting frame 21 and urged by springs 22 to the normal positions shown. Attached to the said arms are the armatures 23 and 24 of actuating magnets 25 and 26, respectively, the latter being suitably mounted on the said supporting frame.

The spacing of the ratchet teeth 18 and the shapes thereof, and the strokes of the actuating pawls 16 and 17 are such that alternate operation of the pawls is necessary to advance the ratchet 15 and shaft 9 step-by-step. For example, with the described elements in the home position as shown, the stroke of pawl 17 is insufficient to advance the ratchet one step, therefore, it is understood, that energization of magnet 26 at this particular time is ineffective to advance the ratchet. However, energization of magnet 25 is effective, at this time, to cause advancement of the ratchet one step, by attracting its armature 23, and effecting a partial clockwise rotation of arm 19, thereby urging the spring urged pawl 16 upwardly to engage one of the ratchet teeth. The advancement just effected is sufficient to position one of the ratchet teeth in the path of the pawl 17, whenever the related magnet 26 is energized. Until the latter magnet is energized, additional energizations of magnet 25 are ineffective to cause further advancement of the ratchet.

Attention should also be directed to the fact, that the ratchet teeth are shaped, so that when one of the magnets is energized to attract its related armature and effect partial rotation of the associated arm, the free end 27 of the said arm (at the end of its stroke) engages directly one of the teeth, thereby preventing overthrow of the ratchet and also locking the ratchet in the advanced position, as long as the said magnet is energized. The advantages of this arrangement will be understood as the description progresses. Each of the conducting rings 10 and 11 are secured on individual insulating collars 28, which collars are suitably secured to the shaft 9. One of the collars is hollowed at one end to receive the conducting ring 12, which ring as well as ring 13, is secured to the shaft 9 in conductive relationship thereto. The conducting ring 12 is provided with four radially extending conducting segments 12a—12d. Four equally spaced conducting segments 10a—10d and 11a—11d, which are integrally formed extensions of the conducting rings 10 and 11, respectively, are provided to extend across the periphery of the related insulating collar as shown. Two groups of arcuately arranged conducting brushes, namely, B1, B3, B5, BP, BS, BC3, and B2, B4, B6, BC1, BC2, are provided, and are supported by the insulating members 29, which in turn are suitably secured to the supporting frame 21. The said brushes are fixed in different planes, and positioned so as to cooperate with the following sections of the conducting rings: brushes B1, B3, B5, and BP are positioned to extend in the path of the conducting segments 11a—11d,

brush BS is positioned to extend in the path of the conducting segments 12a-12d, and brush BC3 is positioned to engage continuously the conducting ring 11; brushes B2, B4, B6 are positioned to extend in the path of the conducting segments 10a-10d, brush BC2 is positioned to engage continuously the conducting ring 10, and brush BC1 is positioned to engage continuously the conducting ring 13.

As mentioned, upon alternate energization of the magnets 25 and 26, the said conducting rings and associated segments are advanced, from the home position shown, to engage different ones of the associated conducting brushes. Each step, of the advanced rings and segments, is equivalent to a distance equal to half the distances separating the conducting tips of the equally spaced brushes BP, B1, B3, B5 and B2, B4, B6. The width of each of the conducting segments 10a-10d and 11a-11d is approximately equivalent to one half the distances separating the conducting tips of the latter mentioned brushes. The width of each of the conducting segments 12a-12d is approximately half of the width of one of the segments 10a-10d or 11a-11d. During eight successive steps of advancement of the said rings and segments, a complete cycle of operation of the associated brushes is effected. At the home position shown in Figs. 2 to 4, and diagrammatically indicated in Figs. 1 and 10, the brush BS engages the conducting segment 12b, brush BP engages the conducting segment 11a. Since brushes BC1, BC2, and BC3 engage continuously the related conducting rings no reference will be made to these brushes during the following analysis.

Upon completion of the first step, the contact between segment 11a and brush BP is broken, the contact between segment 12b and brush BS is broken, and contact is made between conducting segment 11b and brush B1. Upon the second step, the segment 11b remains in contact with brush B1, and contact is made between segment 10b and brush B2; the third step, the contact between segment 11b and brush B1 is broken, and contact is made between the said segment and brush B3, the segment 10b remains in contact with brush B2; fourth step, the contact between segment 10b and brush B2 is broken, and contact is made between this segment and brush B4, the segment 11b remains in contact with brush B3; fifth step, the contact between segment 11b and brush B3 is broken, and contact is made between this segment and brush B5; the segment 10b remains in contact with brush B4; sixth step, the contact between segment 10b and brush B4 is broken, and contact is made between this segment and brush B6, the segment 11b remains in contact with brush B5; seventh step, the contact between segment 11b and brush B5 is broken, and contact is made between this segment and brush BP, the segment 10b remains in contact with brush B6; eighth step, the contact between segment 10b and brush B6 is broken, contact is made between segment 12c and brush BS, and the segment 11b remains in contact with brush BP. The conducting rings and segments and the related brushes are now in a home position, similar to the one indicated in the figures.

The purpose of the described arrangement of brush connections, during one cycle of operation of the impulse distributing means, will be explained during the description of the circuit diagram in Fig. 1. The oscillatory means for 78

controlling the operation of the said distributing means will now be described.

Oscillatory control means for impulse distributing means

5 Referring now to Fig. 1, one type of oscillatory control means is shown to comprise the electron discharge device T1, the anode 30 of which is connected to one terminal of the primary winding 10 31 of transformer 32, the other terminal of which is connected by conductor 33 to the terminal 34 of a suitable power supply. The circuit connected to the grid 35 includes the resistor 36 and the secondary winding 37 of the transformer 32. 15 The latter winding has an intermediate connection from point 38, by conductor 39, to terminal 40 of the said power supply. One terminal of the secondary winding is connected to resistor 41, which in turn is connected, by conductor 42, to grids 43 and 44 of the electron discharge devices T2 and T3, respectively, which are of the twin triode type. An adjustable capacitance 45 and resistance 46 are connected in shunt relationship with the secondary winding 37. The cathode elements of devices T1-T3 are connected, by conductor 47, to the terminal 48 of the power supply. The circuit connected to grid 49 of device T2, includes resistor 50, and is connected to resistors 36 and 46 at the point indicated 51. 20 25 The grid 52 of device T3 is connected, by conductor 53, to grid 35 of device T1, and by conductor 54 to brush BC1. The anodes 55 and 56 of device T2 are connected to the actuating magnets 25 and 26 respectively, whereas, the anodes 57 and 58 of device T3 are connected to the brushes BC2 and BC3, respectively.

The circuit connections of the grid, cathode and anode elements of device T1 described are the conventional connections for causing the device T1 to operate as an electron oscillator. The frequency of the generated oscillations can be determined by the adjustable capacitance 45, or if desired the magnetic gap of the transformer 32 may be made variable and adjustable, as indicated by the dotted arrow. An additional control circuit can be traced from terminal 44 of the power supply to conductor 59, normally closed contacts CS, resistance 60, brush BS, segment 12b, conducting rings 12 and 13, brush BC1, conductors 54 and 53, grids 35 and 52 of devices T1 and T3, respectively, resistance 36, secondary winding 37, conductor 39, terminal 40 of the power supply, resistance 61 to terminal 48 of the power supply.

55 Whenever, the circuit just traced is open, a biasing potential is impressed upon the said grids 35 and 52, due to the connection from the said grids to terminal 40 of the power supply. However, when the said traced circuit is connected to the grids 35 and 52, the voltage drop across resistance 36 is effective to neutralize the said biasing potential referred to, thereby placing the grids 35 and 52 at substantially zero biasing potential. The values of resistances 36 and 60 are determined and chosen, so that the said voltage drop across the former is sufficient to neutralize the biasing potential impressed by the circuit from terminal 40 of the power supply to grids 35 and 52.

70 Under the last mentioned conditions, the device T1 is conductive, causing a constant current flow in the circuit from terminal 34 of the power supply, the primary winding 31, anode element 30, the related cathode element, conductor 47 to terminal 48 of the said power supply, to establish a

predetermined and constant magnetic field around the transformer 32, thereby placing the circuits connected to the elements of device T1 in a non-oscillating condition.

Now, whenever the positive potential from terminal 34 is removed from the grid 35, for example, by opening the contacts CS, the neutralizing voltage drop across resistance 38 is removed, and the biasing potential impressed upon the said grid instantly is changed from zero to a negative value, thus rendering the device T1 non-conductive momentarily, and thereby cutting off the flow of current through winding 31, and causing the said magnetic field of transformer 32 to collapse. At this moment, a voltage is induced across winding 37 which tends to render the grid more negative with respect to its cathode, and causes the condenser 45 to be fully charged. Upon discharge of the said condenser the grid 35 becomes positive, with respect to the cathode, to render the device conductive momentarily to energize the winding 31. In this well known manner, oscillations of a frequency determined by the chosen C and L values of the said capacitance and inductance are generated continuously while the positive potential from terminal 34 is not impressed upon the grid 35. However, when the said positive potential is impressed thereupon, by closing the contacts CS for example, the generation of the oscillations is interrupted. In this manner, an oscillation generator is provided, which can be started and stopped in the manner described, whereby the generated oscillations at the very start of its operations are virtually of maximum amplitude, and upon stopping the operations of the generator the generation of oscillations is stopped instantly. Fig. 5 shows the voltage wave shapes of the oscillations generated for a chosen cycle of operation, namely, four complete oscillator cycles.

It is noted, that the grids 43 and 49 of device T2 are connected in push-pull relationship to the terminals of winding 31, so that upon operation of the oscillation generator, the two triode sections of device T2 are rendered conductive alternately. In this manner, the actuating magnets 25 and 26 are energized alternately, in the order mentioned, to operate the impulse distributing means, by advancing the conducting rings and segments, step by step, for a chosen cycle of operations.

It should be mentioned, that although the grid 49 of device T2 is connected to the same terminal of winding 31 as grid 35 of device T1, the potential impressed thereupon normally is negative with respect to its cathode, and not of zero value as in the case of grid 35. The reason for this being, that grid 49 is connected to point 51 through a series resistor 50. Therefore, the triode section of device T2 controlled by grid 49 is not fully conductive, at the times when the positive potential from terminal 34 is impressed upon grid 35 of device T1, to render the latter fully conductive. In fact, at such times, a relatively small and negligible amount of current flow is present in the circuit connected to anode 56, so that normally very little current flow passes through the winding of magnet 26, and consequently a negligible amount of energy for the latter need be dissipated.

Transmitting circuit arrangement

With reference now to the circuit connection shown in the upper half section of Fig. 1, the permutatively controlled contacts C1-C6 of the

transmitting unit 66 are shown connected to the individual brushes B1-B6 of the impulse distributing means, and by a common conductor 66 are connected to the anode-cathode circuit of electron discharge device 67 and the brush BP. It is well known, that the said contacts can be controlled in a permutative manner in accordance with the selected character operations of the transmitting unit. It is equally well known, that the normally closed contacts CS are opened for each permutative setting or operation of the contacts C1-C6.

It was explained in detail, that device T1 normally is conductive continuously, whenever the contacts CS are closed, and with the impulse distributing means positioned in the normal home position shown. Grid 52 of device T2 is connected in parallel to grid 35 of device T1, and consequently the triode section controlled thereby is fully conductive, when the contacts CS are closed and with the said distributing means in the said normal position.

For these conditions, a circuit can be traced from terminal 48 of the power supply to conductor 47, cathode and anode 58 of device T2, brush BC3, conducting ring 11 and segment 11a, brush BP to the cathode element of device 67. The electron discharge device 67 is a twin triode type connected as an oscillator, the frequency of which is determined by the C and L values of the capacitance 68 and transformer 69. The center tap of the primary winding of said transformer is connected to terminal 34 of the power supply, and the terminals of said winding are connected to the anode elements of device 67. Each anode is coupled to the opposite grid by means of condensers 70 and 71, and the grid elements are connected to cathode through the grid leak resistors 72 and 73.

From the foregoing description, it should be evident and adequate for the present purpose to state, that, when sufficient potential is applied between the center tap of the primary winding of transformer 69 and the cathode of device 67, oscillations of a predetermined frequency are generated, and that when this potential is removed, the generation of said oscillations is interrupted. The generated carrier oscillations are impressed upon the signal line terminals 74 through the volume control device 75. It has been found desirable, particularly when utilizing the system for telephone line transmission purposes, that the signal carrier frequency should be set for approximately 1800 cycles, and depending upon the desired speed of operation, the base frequency of the oscillations generated by device T1 can be approximately from 20 to 50 cycles.

Now, so long as the triode section of device T3 controlled by grid 52 is conductive, sufficient potential is impressed upon the described input circuit of device 67 to render the latter operative to generate the signal oscillations, which in turn, are impressed upon a suitable transmission medium. This signal is indicated at A in Fig. 6, and corresponds to the continuous line signal, or current condition, impressed upon the transmission medium, during the absence of character signals, in the present day start-stop systems.

From the foregoing description, it is understood that, upon each operation of the transmitting unit to position the contacts C1-C6, contacts CS are opened, momentarily, to render the oscillator device T1 effective to generate oscillations, and effect energization of the magnets 25

and 26, alternately, to cause the conducting rings and segments to sweep across the associated brushes. It was also mentioned that eight steps of the said conducting rings represent a complete signaling cycle, so that the brush BS, at the end of each series of eight steps, engages one of the conducting segments 12a—12d, and thereby impresses the neutralizing potential upon the input circuit of device T1, whereupon further generation of oscillations is interrupted (assuming of course, that during the signaling cycle the contacts CS are closed which is the normal practice). It should be stated, at this time, that, it is assumed, the sections indicated 1, 3, 5 and 7 of the oscillations in Fig. 5 are effective to render the grid 43 positive, and cause the magnet 25 to be energized during the signaling cycle, and that sections 2, 4, 6, and 8 are effective to render the grid 49 positive to cause the magnet 26 to be energized, during the said cycle.

In order to complete the description of the transmitting circuit arrangement, it will be explained briefly, how the permutation signals are generated, therefore, assume that the transmitting unit 65 is operated to close the contacts C1, C4 and C5 during the signaling cycle, and that contacts CS are opened momentarily. Normally, the continuous signal indicated at A in Fig. 6 is impressed upon the transmission medium. Upon opening of the contacts CS, grids 43 and 49 are rendered positive, alternately, due to the operation of device T1 as explained. Grids 44 and 52, similarly are rendered positive, in synchronism with grids 43 and 49, respectively. Therefore, during the first half cycle of oscillation of device T1, the potential impressed on grid 52 drops to below a normal plate current cutoff value, and the potential impressed on grid 35 is positive to render the related triode section conductive. Thus, during the said first half cycle of operation, when the conducting rings are advanced one step, the oscillator device 67 is rendered inoperative, and consequently no signal oscillations are impressed upon the line terminals 74. This condition is indicated at B in Fig. 6.

Since current flow, in the circuit connected to anode 58, is instantly cut off when contacts CS are opened, during the first half cycle of operation when the conducting rings are advanced one step, there is no current flow through brush BP, when this contact is broken. Similarly, when contact is made with brush B1, even though contact C1 is closed, no current flows through the circuit associated therewith, at this time in the cycle.

During the second half cycle of operation of device T1, brush B1 remains in contact with its conducting segment, and, since grid 52 is now positive and grid 44 negative with respect to cathode, current flows from the terminal 34 of the power supply to anode-cathode circuit of device 67, conductor 66, contacts C1, brush B1, one of the segments 11a—11d, conducting ring 11, brush BC3, anode 58 and related cathode, to conductor 47 and terminal 48 of the said power supply, thereby rendering the device 67 conductive, during this said half cycle, which is indicated at C in Fig. 6, to transmit the first signal of the combination. Also, during this half cycle, contact is made with brush B2, however, since contacts C2 are open, and since grid 44 is negative, at this time, the circuit connected to anode 57 is maintained non-conducting.

During the third cycle of operation of device

T1, grid 44 becomes positive and grid 52 negative, thus rendering the oscillator device 67 non-conductive. Since contacts C2 are open, no signaling circuit can be completed through brush B2. This condition is indicated at D in Fig. 6.

During the fourth cycle of operation of device T1, contact is broken with brush B2 and made with brush B4, but no current passes through the latter, even though contacts C4 are closed, due to the negative grid 44, and with contacts C3 open, a circuit cannot be completed through brush B3. Thus, no signal is impressed on the transmission medium, at this time, in the signaling cycle, as indicated at E in Fig. 6.

During the fifth cycle of operation of device T1, brush B4 remains in contact with conducting ring 11, and since contacts C4 are closed, and the grid 44 is positive, at this time, a circuit is completed to render the oscillator device 67 conductive, as indicated at F in Fig. 6. Contact is broken with brush B3 and made with B5, however, current cannot flow through the latter due to grid 52 being negative.

During the sixth cycle of operation of device T1, current is permitted to flow through brush B5, due to the positive grid 52, thereby rendering the oscillator device 67 conductive, at this time, as indicated at G in Fig. 6.

During the seventh cycle of operation of device T1, grid 52 becomes negative to render device 67 non-conductive. Contact is made with brush BP, but, due to the condition of grid 52, no current can flow through this circuit at this time. Grid 44 is positive, but no current can flow through brush B6, since contacts C6 are open. This condition is indicated at H in Fig. 6.

During the eighth cycle of operation of device T1, contact is made with brush BS to render the oscillator device T1 conductive continuously. Current also flows through the brush BP, since grid 52 is now positive with respect to cathode, thereby rendering the device 67 conductive to generate the continuous signal condition, which is impressed on the transmission medium, during the absence of character signals. This condition is indicated at A in Fig. 6. In this manner, the permutation signals are initiated and transmitted, during a signaling cycle, by means of the novel distributing means.

Receiving circuit arrangement

Referring again to Fig. 1, the receiving circuit connections, shown in the lower half section of the figure, are similar to those of the transmitting circuit, just described. The impulse distributing means, at both transmitting and receiving stations, are identical in structure and operation, as well as the control circuits associated with the devices T1, T2 and T3. Similar reference characters are used to denote like elements and circuits. For this reason, it is not deemed necessary to repeat the detailed description of the operation of these like elements and circuits.

Control magnets M1—M6 of a suitable printing telegraph receiving unit, indicated generally by the reference character 80, are connected to the individual brushes B1—B6 of the impulse distributing means. The said magnets are also connected, by a common conductor 81, to the cathode-anode circuit of electron discharge device 82, and by means of conductor 83 are connected to brush BS through the resistor 68. It is well known, how the control magnets M1—M6 are effective to control the operation of permutation members, for effecting the selection of the

character type elements, in accordance with the character code signals received.

In the present system, an additional control magnet MP, for controlling the printing operations, is employed. The specific control function of this magnet will be described later. It will suffice to say, for the present, that this control magnet is energized upon receipt of the permutation code signals to effect the printing operations. One terminal of the said magnet is connected to brush BP, and the other terminal is connected by conductor 84 to terminal 34 of the power supply.

The terminal apparatus for receiving the signals is shown to comprise a full wave rectifier discharge device 85, the separate anodes of which are connected to the terminals of the secondary winding of the transformer 86, the primary winding of which is connected to the terminals 87, and shunted by a signal amplitude limiting resistor 88. A center tap connection is provided from the secondary winding to one terminal of resistor 89, the other terminal of which is connected to the cathode of device 85, and grid element of device 82. Biasing potential is supplied by battery 90, and impressed upon the grid of device 82 to render the latter non-conductive, when no signals are received.

Assume now, that the continuous signal represented by A in Fig. 6 is impressed upon the terminals 87 and device 85. The signal oscillations are rectified by device 85, which in turn, impresses a continuous DC rectified voltage across resistor 89, which DC potential is of such value, as to overcome the biasing potential impressed upon the grid of device 82, thereby rendering the latter conductive. A circuit can then be traced from terminal 34 of the power supply, anode-cathode of device 82, conductor 81, resistor 88, brush BS, conducting segment 12b and related conducting rings 12 and 13, brush Bc1, conductor 34, grids 35 and 52 of devices T1 and T3, respectively, resistor 38, winding 37, conductor 39, resistor 61 to terminal 48 of the said power supply. Thus, as described hereinabove in connection with the transmitting circuit, the biasing potentials impressed on said grids are overcome or neutralized, so that the related triode sections are rendered conductive continuously. Another control circuit can be traced from terminal 34 of the power supply to conductor 84, magnet MP, brush BP, conducting segment 11a and ring 11, anode 88 and related cathode, to conductor 47 and terminal 48 of the said power supply, thus energizing the said magnet, whenever the impulse distributing means is in the home position indicated, and a signal is impressed upon the said signal receiving means.

In order to simplify the description to follow, it will be assumed, that the described signal combination initiated by the operation of contacts C1, C4 and C5 is impressed upon the signal receiving means. The first signal of the combination is the start signal condition, represented at B in Fig. 6, by having no signal oscillations impressed upon the receiving means. As mentioned, for this condition, no potential is impressed across resistor 89, and consequently device 82 is rendered non-conductive, thereby removing the neutralizing potential impressed upon grids 35 and 52. Device T1 now is conditioned to function as an oscillator, and effective to control the alternate operations of the actuating magnets 25 and 26 of the impulse distributing means. The described circuit connected 75

to anode 88 also becomes non-conducting, due to the said conditioning of grid 52, thereby effecting the deenergization of the print magnet MP. The frequency of the oscillatory means at the receiver is adjusted, so as to approximately be the same as that of the transmitter, and under these conditions, it has been found, that the two impulse distributing means will operate in synchronism.

During the second stepping operation of the distributing means, the first signal of the combination is received to establish the following circuit: From terminal 34 of the power supply to the anode-cathode elements of device 82, conductor 81, control magnet M4, brush B4, conducting segment 11b and ring 11, brush BC2, anode 88 and related cathode, to conductor 47 and terminal 48 of the said power supply, energizing said magnet.

During the third and fourth stepping operations of the distributing means, no circuits are established, due to the absence of control signals. But, during the fifth stepping operation, a circuit is established from terminal 34 of the power supply to anode-cathode elements of device 82, conductor 81, magnet M4, brush B4, conducting segment 10b and ring 10, brush BC2, anode 57 and related cathode to conductor 47 and terminal 48 of the power supply, energizing said magnet. During the sixth stepping operation, a circuit is established to magnet M5, through brushes B5 and BC3 to anode 28, to effect energization of this magnet. During the seventh stepping operation no signals are received, and during the eighth and last stepping operation in this signaling cycle, the conducting rings are positioned to a home position to effect energization of the print magnet MP, through the circuit traced hereinabove, thereby completing the cycle of operations.

Upon energization of the print magnet, the character is printed in accordance with the selection effected by the energization of the said control magnets. One embodiment of a receiving teleprinter, utilizing a print magnet as referred to, will now be described.

Receiving teleprinter unit

In certain applications of the system just described, the oscillator devices T1 may be adjusted to operate at a relatively low frequency rate, and consequently transmit and receive the timed character signals, at too slow a rate, to operate satisfactorily the printer unit, referred to in U. S. Patent No. 2,165,247. To overcome this condition, certain modifications of the structural details of this unit have been suggested, whereby the received signals are stored by the control clutch units associated with the permutation bars. Upon receipt of the signals of each combination, the print control magnet is energized to effect the selection of the character type elements and recording of the characters. With reference now to Figs. 7-9, the changes referred to will be described.

The rotatable permutation bars 100, of which six are shown, are provided with individual clutch units, comprising an annular member 101, secured to a related bar, which member is shaped to receive a movable dog 102. The said dog is provided with a single tooth 103 normally held out of engagement with the associated ratchet wheel 104. A pivoted dog lift lever 105 is provided to control the positioning of the dog, and normally is engaged by clutch stop arm 106 se-

cured to armature 107 of magnet M1, which is one of the control magnets M1—M6 referred to.

It is described in detail in Patent No. 2,165,247, how the main drive gears, one of which is indicated by the reference character 108, are driven to effect continuous rotation of the individual gears 109, and the related stud shafts 110, which shafts in turn cause the rotation of the associated ratchet wheels 104.

Referring now to the dog lift lever 105 (see Fig. 9a), it is noted, that two individual stops 111 and 112 are formed thereon, and arranged one below the other in offset positions with respect to each other. The upright section of the cooperating stop arm 106 is provided with a U-shaped slot 113 in one side thereof, so that the uppermost section 114 of the stop arm can engage the upper stop 111 of the dog lift lever 105, whenever the armature 107 is in a released position as shown. In this manner, the dog 102 is held in a position, so that its tooth is prevented from engaging the associated rotating wheel, and consequently, preventing the associated permutation bar from being rotated or operated.

Now, upon energization of the related control magnet, for example magnet M1, the stop arm 106, as viewed in Fig. 9, is partially rotated in a clockwise direction, thereby resulting in the disengagement of the stop section 114 and upper stop 111 of the dog lift lever, and the engagement 30 of the said stop section with the lower stop 112 of the dog lift lever. This resultant action is quite similar to actions of well known escapement mechanisms. The escapement action is positive, due to the fact that the dog 102 is constantly urged, by spring means (not shown in the present application but described in detail in the Patent 2,165,247), in the direction of the ratchet wheel. The stop arm 106 is retained in the shifted position, by means of a frictional lock, comprising the spring urged ball 115 engaging the uppermost notch 116 formed in the side opposite the one with the slot 113 of the upright section of stop arm.

It is evident now, that, as the control signals are impressed upon the individual magnets M1—M6 to effect energization thereof, the said signals are effective to cause the controlled clutch units to be shifted as described, and store the corresponding signals until the clutch units are released completely to effect rotation of the related permutation bars.

The release of each clutch unit is under control of the print magnets MP, only one of which is shown, however it will be understood, that one print magnet is provided for each group of three control magnets included in the printer unit. The said print magnet is mounted below the related group of control magnets, and is provided with a pivoted armature 117 to which an extension arm 118 is secured, there being an extension arm for each related control magnet. The said extension arms are adapted to engage the displaced or shifted stop arms 106, upon energization of the print magnet MP, to restore the said arms to the normal position shown. Upon restoration of a stop arm 106, the uppermost section 114 thereof is disengaged from the lower stop 112, thereby releasing the dog lift lever 105 and permitting the tooth of the dog 102 to engage the related ratchet wheel. This operation results in the rotation of the associated permutation bar. Upon completion of a revolution of the bar and clutch unit, the upper stop 111 of the dog lift lever again engages the uppermost sec-

tion 114 of the restored stop arm, to effect disengagement of the said dog tooth and ratchet. Thus, it is seen, that all the shifted clutch units are released, upon energization of the associated print magnet MP, to effect rotation of the related permutation bars, after the different signals of the permutation combinations are received and stored.

Each permutation bar 100 is provided with a plurality of diametrically opposed slots 119, which bars upon rotation, in permutative groups, present certain of the said slots under the control levers 120, so that one control lever is selected and permitted to drop in the channel provided by those slots which are in alignment. The selected control lever is then effective to operate its attached key bar lever (not shown), to cause the character to be recorded, in accordance with the code signals impressed upon the control magnets M1—M6.

Two way operation

Referring now to Fig. 10, the description of the preferred embodiment of a two way system will be given. The single impulse distributing means, oscillatory control means, and impulse generating means associated therewith are similar in structure and operation as those described in connection with Fig. 1. Similar reference characters are used to denote like elements and circuits, and therefore this description will not be repeated here.

To simplify the following, the description will be limited to the control elements and circuits of one station, it being understood that any number of stations employing similar elements and circuits may be included in the system.

At each station, a send-receive switch S is provided, which comprises a plurality of transfer contacts S1—S6. The contacts are shown in the "send" position which will be referred to as the normal position. In this position, the switch is effective to condition the connected circuits, so that the contacts C1—C6 and CS are effective to control the operations of the start-stop distributor and associated control means, whereby code groups of signals can be initiated, and consequently transmitted over the associated transmission medium by the signal transmitting means, described in detail hereinabove, and indicated STM in Fig. 10.

A plurality of signal storage relays R1—R6 are provided, the energization of which are controlled by the contacts C1—C6 with the switch S in the "send" position. Each of the said relays have single transfer contacts designated RC1—RC6. In the normal position shown, the said contacts connect the magnets M1—M6 to the distributor brushes B1—B6. Upon energization of the relays, the transferred contacts RC1—RC6 are connected to the said brushes B1—B6 to control the transmitting means STM, upon operation of the distributor, in accordance with the operated contacts C1—C6.

It is seen, that individual resistor-capacitor elements indicated 150 and 151 respectively, are connected to each relay coil. The purpose of these elements is to prolong selectively the energization of the associated relays, thus insuring that the different contacts RC1—RC6 remain closed at the times the related brushes B1—B6 are engaged by the segments of the respective conducting rings 10 and 11.

Now, with the switch S in the "send" position, and with the contacts C1—C6, and CS in the

positions shown, a circuit can be traced from terminal 34 of the power supply to conductors 33 and 152, normally closed contacts S2, CS, and S1, conductor 153, resistor 60, brush BS, one of the segments of conducting ring 12, conducting ring 13, brush BC1, conductors 54, 53, resistor 36, secondary winding 37, conductor 39, terminal 40 to resistor 61 and terminal 48 of said supply. It is recalled that, by means of the circuit traced, the biasing potentials impressed on grids 35 and 52 are neutralized to render the device T1, and the triode section of device T3 controlled by grid 52, conductive, as long as the contacts CS remain closed.

Another circuit can be traced at this time from said terminal 34, conductors 33 and 152, normally closed contacts S2, signal transmitting means STM, conductor 154, brush BP, one of the segments of conducting ring 11, brush BC3 anode 58 and related cathode, and conductor 47 to terminal 48 of the power supply. In this manner the signal transmitting means STM is effective, as described hereinabove, to impress the continuous signal condition, indicated A in Fig. 6, on the associated transmission medium.

Upon selective operation of the contacts C1—C6, and CS, and to continue with the chosen example, assume contacts C1, C4, and C5 are operated, the relays R1, R4, and R5 are energized. One of the circuits for effecting such energization can be traced as follows: Terminal 34 of the power supply, conductors 33 and 152, normally closed contacts S2, one of the said contacts C1, coil of relay R1 and associated resistor-capacitor network, conductors 155 and 39, terminal 40, and resistor 61 to terminal 48 of the said supply. Upon energization of the relays R1, R4, and R5, the related contacts RC1, RC4, and RC5 are transferred.

Also, upon operation of the contacts C1, C4, and C5, contacts CS are opened momentarily to open the circuit traced, to permit the biasing potential impressed upon grids 35 and 52 to be effective to render the controlled triodes substantially non-conductive. It is understood from the description given, that under these conditions, the device T1 is now adapted to function as an oscillator to control the conductivity of the triode sections controlled by grids 43, 49, 44, and 52 of devices T2 and T3, respectively.

Magnets 25 and 28 are now energized, alternately, for the duration of a signaling cycle, to advance the distributor means eight steps. Due to the transferred contacts RC1, RC4, and RC5, the transmitting means STM is controlled by the control circuits interconnecting the said contacts and brushes B1, B4, and B5, as the said circuits are made available, upon advancement of the conducting rings, under control of the device T3. The code group of signals generated by these circuits, for the chosen example, are shown in Fig. 6.

Upon the completion of eight steps of the distributing means, the described circuits are restored to the normal conditions just mentioned and described in detail hereinabove in connection with Fig. 1.

It is to be noted that the normally closed contacts S3 connect the variable condenser TVC in parallel circuit association with condenser 45 and secondary winding 37. The condenser TVC is adjusted to control the frequency rate of the oscillations generated under control of device T1. The particular operating circumstances are determinate of the predetermined rate to be em-

ployed. However, once the frequency rate is determined, and condenser TVC is adjusted accordingly, it is desired for most conditions to maintain this frequency rate for transmitting purposes. It is seen upon setting of switch S in the "receive" position that contacts S3 are opened and the said condenser is isolated from the oscillator control circuits.

Now, assume that the described station is conditioned for receiving purposes by placing the switch S in the "receive" position. The transferred contacts S3 now connect the condenser RVC in the oscillator control circuits. This condenser is adjusted to control the oscillator T1 so that its oscillation frequency rate is substantially equal to, or preferably slightly greater than the frequency rate of the oscillator at the remotely situated station which is transmitting to the present station conditioned as a receiver. This frequency rate and adjustment, required may differ, as no doubt it would be in practice, from the frequency rate determined by the adjustment of the condenser TVC. Thus, it is seen that the separate control condensers are connected selectively into the common oscillator circuit, depending upon whether it is employed for signal transmitting or receiving purposes.

To continue with the brief description of the present receiver, the continuous signal condition indicated A in Fig. 6 is impressed upon the signal receiving means designated SRM and described in detail in connection with Fig. 1. Upon receipt of this signal, two control circuits are conditioned to maintain the oscillator device T1 in a non-oscillatory condition, and to energize the print magnet MP, respectively. The first circuit can be traced from terminal 34 of the power supply to conductors 33 and 152, transferred contacts S2, signal receiving means SRM, conductor 156, brush BS, one of the conducting segments of ring 12, conducting ring 13, brush BC1, conductors 56 and 53, resistor 36, winding 37, conductor 39 to terminal 40, resistor 61, and terminal 48 of the said power supply. This circuit just traced maintains the device T1 continuously conductive, as well as the triode section controlled by grid 52, for the reasons mentioned hereinbefore. The second circuit referred to can be traced from terminal 48 of the power supply to the cathode-anode of the triode section of device T3 controlled by grid 32, brush BC3, conducting ring 11 and one of its segments, brush BP, conductor 154, transferred contacts S4, magnet MP to transferred contacts S2, and conductor 152 to the terminal 34 of the power supply.

Now, upon receipt of the start signal, the neutralizing potential no longer is impressed upon resistor 36, so that the device T1 can now function as an oscillator. Magnets 25 and 28 are energized alternately to advance the conducting rings eight steps. Upon receipt of the code groups of signals magnets M1, M4, and M5 are energized in the manner described hereinabove. One of these circuits can be traced from terminal 34 of the power supply to conductors 33 and 152, transferred contacts S2, signal receiving means SRM, transferred contacts S5 and S6, magnet M1, for example, normally closed contacts RC1, brush B1, conducting segment of ring 11, brush BC3, anode 58 and related cathode to terminal 48 of the said power supply. In this manner the said magnets are energized to store the signals in the clutch units described. Upon completion of the eight

steps, the distributing means establishes the described circuit to the print control magnet MP which is energized to effect recording of the selected character in accordance with the received signals. Upon receipt of the continuous signal condition A in Fig. 6, the receiving circuits are restored to the conditions described in detail hereinabove.

It should be mentioned that the signal distributing means and associated control circuits are claimed in a copending application Serial No. 370,675, filed Dec. 18, 1940, the distributor means per se in copending application Serial No. 370,676, filed Dec. 18, 1940, and the character recording device including the signal storage means in copending application Serial No. 370,677, filed Dec. 18, 1940.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a printing telegraph system, a station adapted for transmitting and receiving code groups of signals, comprising, in combination, distributor means and actuating control means therefor, means for generating oscillations, start-stop means for rendering the latter effective for controlling the operation of the actuating control means for the duration of a signaling cycle, a plurality of adjustable means, included

in said generating means, for controlling the frequency rates of the generated oscillations, one of the adjustable means having means whereby it is capable of being set for a predetermined frequency rate for the transmission of signals, and another of said adjustable means having means whereby the latter is capable of being set for a different frequency rate for receiving signals, a series of signaling channels, said distributor means having means for making the channels available successively during the said signaling cycle at a predetermined rate, upon operation of the start-stop means, means including said channels for initiating or receiving the code groups of signals, and settable means, in one status, for conditioning the initiating means and the first mentioned adjustable means to be effective to control the distributor means for initiating predetermined code groups of signals at a predetermined rate over said signaling channels during a signaling cycle, and, in another status, for conditioning the receiving means and second mentioned adjustable means whereby the latter is effective to control the operation of the distributor means at a rate commensurate with its setting in order to influence the signaling channels and receiving means in synchronism with the received code groups of signals.

2. The invention set forth in the preceding claim characterized by the fact that the said adjustable means comprise variable capacitance means.

3. The invention set forth in claim 1 wherein means are provided to isolate each adjusting means upon setting of the settable means in one status or another.

CLYDE J. FITCH.
